(No Model.)

O. BUSSLER.

LEAD PENCIL HOLDER.

No. 381,611.

Patented Apr. 24, 1888.

Fig. 1.

Attest

N. E. Bowen.

W. H. Cooke.

Inventor:

Otto Bussler,
By J. C. M. Bowen,
Attorney.

UNITED STATES PATENT OFFICE.

OTTO BUSSLER, OF NUREMBERG, BAVARIA, GERMANY.

LEAD-PENCIL HOLDER.

SPECIFICATION forming part of Letters Patent No. 381,611, dated April 24, 1888.

Application filed January 11, 1886. Serial No. 188,201. (No model.) Patented in England December 18, 1885, No. 15,583.

To all whom it may concern:

Be it known that I, OTTO BUSSLER, of Nu-
remberg, in the German Empire, have made
certain new and useful Improvements in Lead-

5 Pencil Holders, (for which Letters Patent were
granted in England in 1885, No. 15,583;) and
I hereby declare the following to be a full and
clear description thereof.

The nature and object of this invention are
10 fully set forth and described in the subjoined
specific specification, and will be readily un-
derstood by reference to the accompanying
drawings, of which—

Figure 1 is a longitudinal sectional elevation
15 of the improved pencil-holder and its sliding
case, in which view the inner or sliding case
is shown drawn back to the inner limit of its
movement. Fig. 2 is a similar view to Fig. 1,
except that the inner or sliding case is shown
20 thrown partly forward in the outer case. Fig.
3 is an enlarged sectional elevation of the front
end portion of the inner or sliding case, and
also of a part of the pencil-tube. Fig. 4 is a
transverse section of the pencil grip or tongs,
25 taken on the line $x-x$ of Fig. 3. Fig. 5 is an
enlarged sectional elevation of a portion of the
front end of the inner or sliding tube, show-
ing in connection therewith a modified form of
grip or pencil-tongs.

30 The mechanism of this pencil case is con-
tained in an outer case, A, which is made cy-
lindrical or approximately cylindrical in form
and contains concentrically within it the slid-
ing case b. Concentrically arranged within
35 this inner case, b, is a pencil-lead tube, a, which
is fixed relatively to the outer case, A, by a
transverse bar, s, as shown in Figs. 1 and 2, so
that while the intermediate tube or case, b, is
permitted a sliding movement forward and
40 backward the concentric outer case, A, and
the lead-tube a remain relatively stationary.
Slots n n in the shell of the intermediate case,
b, near its rear or inner end, accommodate the
passage of the transverse fixing-bar s, so as to
45 permit the said case b to slide forward and
backward, as desired. A coiled spring, f, con-
centrically surrounds the pencil-tube a and
partially occupies the annular chamber formed
between a and b, as shown in Figs. 1 and 2.
50 The forward end of this spring rests against
the annular collar a', fixed to the exterior of

the stationary central lead-tube, a, and the rear
end of it against the annular collar a', at-
tached to the inner side of the sliding tube b
at its inner end, so that the effect of the said
spring f in its normal condition, thus abutting
55 at its front end to the fixed abutment a' and at
its rear end to the movable abutment a', is to
throw the sliding tube b inwardly into its
housed position, as shown in Fig. 1, but per-
mitting the said sliding tube to be thrown for-
ward or outwardly, as in Fig. 2, by pressing
60 on its rear end, k. The intermediate or slid-
ing tube, b, has an outer section or prolonga-
tion of it, b', secured to its forward end by
screw-threads b', as shown in Figs. 1 and 2.
The extreme front end of this piece b' is cen-
trally apertured, just so as to freely admit the
lead which is to be used in this holder. The
70 rear or inner end of this said piece is cham-
bered out to such a considerable size as to
freely admit the pencil clamps or tongs Z or
Z'. These clamps or tongs may be either sin-
gle-acting, as in Fig. 5, or double-acting, as in
75 Figs. 1, 2, and 3. In either case the said
clamps or tongs are formed of several trian-
gular pieces, as shown in Fig. 4. In the case
of the double-acting clamps or tongs these sec-
tional parts forming them are united and held
80 together by a central band, Z', as shown in
Figs. 1 and 2, and in the case of the single-
acting clamps or tongs the said sectional parts
are united and held together in a base-band, Z',
which is so seated in a converging socket in
85 the forward end of the pencil-tube a as to
habitually press the forward ends, c, of the
tongs-arms together, so as to clamp upon the
pencil. In the case of the double-acting tongs
the rear or inner ends of their several arms
90 are sloped and fitted to a similar inwardly-
converging socket part, so as to habitually
press their inner ends, c', tightly together upon
the pencil-lead.

The advantage of the double-acting tongs or
clamps is that both their ends c and c' closing
95 shearwise press against the embraced lead,
thus forming two points of support, while in
the single-acting clamps or tongs only the outer
ends, c, of said clamps are available as points
of support.

In the pencil-lead holder, described as above,
the chamber in the forward sliding piece, b',

for the accomodation of the lead-tongs, is considerably longer than the said tongs, so as to allow for the forward and backward movement of the said case b b' without contacting 5 with either end of said tongs, so as to interrupt the said sliding movement. The conical chamber in the forward end of the piece b is so shaped and conformed to the front end of the said clamp or tongs pieces Z or Z' as to impinge 10 thereon when the case b b' is drawn inwardly, as in Fig. 1, and thereby the central lead in a is grasped tightly in this position by the several clamp-pieces, the conical or dished cavity in the front end of a , above alluded to, assisting 15 in this clamping movement of the parts; but when the sliding case b b' is thrown forward, as in Fig. 2, the front ends of the clamp or tongs pieces fall back out of the confining conical chamber in b' and release the pencil. 20 Thus it is seen that in the normal position of the parts of this holder—*i. e.*, with the spring f holding the sliding case b b' housed within the outer case, A , as shown in Fig. 1—the conical chamber in the forward end of b' holds 25 the clamps firmly upon the centrally-inclosed lead and in a position for use; but when the sliding case b b' is pressed forward by pressing on k the said forward ends of the clamps Z or Z' are released from holding the said lead, 30 and it is allowed to slide freely in either direction in its said holder, and by holding the open end of the case up or down the lead will slide in or out, as desired, simply by the action of gravity.

The pointed or **V**-shaped formation of the 35 grasping ends of the clamp or tongs pieces, above described, and shown in Fig. 4, assists to hold the lead firmly in its said clamps or tongs.

Having thus described my invention, what I 40 claim as new, and desire to secure by Letters Patent, is—

1. The outer casing and the fixedly secured lead-containing tube, combined with the sliding tube b , provided with a conically-aper-tured front extension, a clamping device loosely seated in the upper end of the lead-containing tube and capable of a slight longitudinal move- 45 ment within said front extension of the sliding tube, and an actuating spring whereby the jaws 50 of the clamping device are normally held closed around the head passing through the lead-con-taining tube, substantially as set forth.

2. The outer casing, A , lead containing tube a , sliding tube b , provided with a front pro- 55 jection, b' , having a conically-shaped interior, spring f , and clamping device Z Z' , resting on a conical seat at the top of said lead-contain-ing tube, substantially as set forth.

In witness whereof I have hereunto set my 60 hand in presence of two witnesses.

OTTO BUSSLER.

Witnesses:

OSCAR MÜHLNER,
B. ROI.
